UNITED STATES PATENT OFFICE.

ALWIN G. STEINMAYER, OF MILWAUKEE, WISCONSIN, ASSIGNOR TO LINE MATERIAL COMPANY, OF SOUTH MILWAUKEE, WISCONSIN, A CORPORATION OF WISCONSIN.

ELECTRICAL SWITCH.

Application filed July 31, 1924. Serial No. 729,317.

This invention relates to certain new and useful improvements in electrical switches and refers more particularly to a cut-out switch having as one of its objects the provision of means for insuring the quick breaking of a current to minimize arcing at the contacts.

Another object of this invention resides in the provision of an electrical switch of the character described including an auxiliary switch blade or member adapted to remain in circuit closing position until after the other blades forming a master switch have been moved to circuit opening position a predetermined degree, when the auxiliary switch is quickly moved to open position to produce a quick break of the circuit.

My invention contemplates as another object the provision of an electrical switch having an auxiliary switch for producing a quick break in the circuit which carries its share of the current when the switch is closed.

It is a further object of this invention to provide means operable upon the failure of the auxiliary switch to open upon predetermined movement of the master switch to force the auxiliary to circuit breaking position, thus providing a factor of safety.

This invention has as a still further object the provision of an electrical switch of the character described which is of simple construction and which may be used in any place or in connection with any current.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a front view of an electrical cutout switch embodying my invention and illustrating one of its uses;

Figure 2 is a side view of the switch, and

Figure 3 is a view similar to Figure 2, parts thereof being broken away and in section, illustrating the outer or master switch blades in open position prior to the opening movement of the inner or auxiliary switch blade.

Referring now more particularly to the accompanying drawing, in which like numerals designate like parts throughout the several views, the numeral 5 designates a housing or box having its open side normally closed by a hinged door 6. The rear wall 7 of the housing carries suitable means (not shown) for facilitating its mounting to a cross-arm or other support, and the side walls have two lead-in openings therein in which insulators 8 and 9 are secured. The line 10, in the circuit of which the switch is included, has its end 11 passed into the housing through the insulator 8 and electrically connected with a stationary contact 12, to be later described, by a terminal 13, and the other end 14 of the line enters the housing through the insulator 9 and is connected with a stationary contact 15 similar to contact 12, by a terminal 16.

The stationary contacts 12 and 15 are preferably identical in construction and are mounted in the housing by suitable porcelain or insulating bases 17 and 18, respectively, illustrated in the drawing as of the petticoat type. The stationary contacts are of the clip type and each comprise two outer spring clips 19 between which are mounted a pair of spaced inner spring clips 20 between which switch blades 21, 22 and 23 are frictionally engageable.

The switch blades are spaced a distance substantially equal to the thickness of the clips 20, the outer blades 21 and 23 being connected to form a main or master switch independently of the inner blade which forms an auxiliary or quick-break switch. The blades 21 and 23 are connected at their upper ends by a pull ring 24 by fastenings 26 passed therethrough and a lug 25 formed on the pull ring and positioned between the outer ends of the blades to properly space the same. The lower ends of the outer blades are pivotally secured to and spaced by a standard 27, the upper end of which is positioned between and secured to the blades by a pin 28. In this manner the outer blades forming the main switch are pivotal-

ly mounted for movement to and from electrical engagement with the stationary contacts 12 and 15.

The center blade 22 forming the auxiliary switch is normally positioned in the space between the outer blades and has its lower end pivotally secured thereto by a pivot pin 29, the center blade being maintained in proper position by spacing washers 30 mounted on the pivot pin between the blades. The upper end of the center blade is spaced by a guide clip 31 of substantially U-shape and secured to the outer blades, as at 32, and having its ends 33 slightly flared, for the purpose hereinafter described.

The center blade or auxiliary switch is normally retained in its position between the outer blades, to, with the outer blades, form a movable switch contact, by a spring 34 the medial portions of which are coiled about extensions 35 on the pivot pin 28 with its ends 36 bearing against the opposite sides of the movable switch contact outwardly of the pivot pin 29. As a result, movement of the center blade from between the outer blades is yieldably resisted by the spring. Closing movement of the outer blades causes the closed end of the guide 31 to carry the center blade with them to engagement with the stationary contacts.

In operation, assuming the parts to be in their positions illustrated in Figures 1 and 2, the end 37 of a pull stick 38 is inserted in the aperture of the eye 24 and a pull exerted when it is desired to break the continuity of the circuit. As the blades 21 and 23 disengage the stationary contacts, the friction between the clips 20 and the center blade retains the latter in circuit making position until the outer blades reach a predetermined position and have stored sufficient energy in spring 34 to disengage the auxiliary and stationary contacts. At this point the center blade is moved with a quick, snappy action, minimizing arching incidental to the breaking of the circuit, the center blade being guided between the outer blades by the flaring ends 33 of the guide.

In the event spring 34 has become broken or too weak to move the center blade against the resistance offered by its frictional engagement with the stationary contacts, continued movement of the outer blades beyond a point where the center blade should function, the squared end 39 of the center blade, which extends below the pivot pin 29 a short distance, rides over the slightly curved corner 40 of the outer end of the standard 27, which acts as a cam. This cam action forces the center blade out of engagement with the stationary contacts, providing a factor of safety against the breakage or weakening of the spring 34.

From the foregoing description taken in connection with the accompanying drawings

it will be readily obvious to those skilled in the art to which an invention of this character appertains that I provide an improved electrical switch having an auxiliary switch for obtaining the quick breaking of the circuit and also carrying its share of the current and that the switch may be employed in other places than with a box or housing of the type illustrated.

What I claim as my invention is:

1. In an appliance of the character described, a support, a stationary contact mounted on the support, a standard fixed to the support and spaced from the stationary contact, a movable contact electrically engageable with the fixed contact and including a plurality of switch blades, means connecting the outer blades of the movable contact at their outer ends, the inner ends of the outer blades being disposed on opposite sides of the standard, means pivotally connecting the outer blades with the standard, and means pivotally connecting the inner blade with the outer blades adjacent their point of pivotal connection with the standard, the inner end of the inner blade being approximately square and terminating adjacent the standard whereby opening movement of the movable contact disengages the outer blades and leaves the inner blade in engagement with the stationary contact until one corner of the inner end thereof engages the standard when said inner blade moves in unison with the outer blades.

2. In an appliance of the character described, a support, a stationary contact mounted on the support, a standard fixed to the support and spaced from the stationary contact, and a movable contact adapted to be engaged with the stationary contact and including a plurality of switch blades, the inner blades terminating short of the ends of the outer blades, means connecting the outer blades of the movable contact at their outer ends, the outer ends of the blades being disposed on the opposite sides of the standard, means pivotally connecting the outer blades with the standard, means pivotally connecting the inner end of the inner blade with the outer blades adjacent their point of pivotal connection with the standard, and a spring member medially coiled about the pivot of the outer blades and having its ends bent over the opposite edges thereof to normally yieldably secure the inner blade in its position concealed between the outer blades and a substantially U-shaped clip member secured over the outer blades adjacent the outer free ends thereof and extended therebelow with its ends flared to form a guide for the inner blade in its movement between the outer blade, the closed end of said clip preventing pivotal movement of the inner blade outwardly beyond the outer blades.

3. An appliance of the character described,

a stationary contact including a pair of spring clips having a pair of spacers mounted therein, a movable contact including three longitudinally spaced blades adapted to be 5 electrically connected with the stationary contact with the spacers engaged between the blades, the outer blades of the movable contact being pivotally mounted to a support, means pivotally mounting the center blade 10 and the movable contact to the outer blades whereby independent movement thereof is permitted, and a substantially U-shaped clip secured between the outer blades adjacent their outer ends and having its ends flared to provide a guide for the inner blade as it 15 moves into its normal position between the outer blades, said clip providing a spacer for maintaining the center blade in proper longitudinally spaced position between the outer blades. 20

In testimony whereof I affix my signature.
ALVIN G. STEINMAYER.

a stationary contact including a pair of permitted, and a substantially U-shaped clip
spring clips having a pair of spacers mounted secured between the outer blades adjacent
therein, a movable contact including three their outer ends and having its ends flared
longitudinally spaced blades adapted to be 15
electrically connected with the stationary to provide a guide for the inner blade as it
contact with the spacers engaged between the moves into its normal position between the
blades, the outer blades of the movable contact being pivotally mounted to a support, outer blades, said clip providing a spacer for
means pivotally mounting the center blade maintaining the center blade in proper
10 and the movable contact to the outer blades longitudinally spaced position between the
whereby independent movement thereof is outer blades. 20

In testimony whereof I affix my signature.
ALVIN G. STEINMAYER.

CERTIFICATE OF CORRECTION.

Patent No. 1,656,399.

Granted January 17, 1928, to

ALWIN G. STEINMAYER.

It is hereby certified that error appears in the printed specification of the above numbered patent requiring correction as follows: Page 3, end of specification, signature of applicant, for "Alvin G. Steinmayer" read "Alwin G. Steinmayer"; and that the said Letters Patent should be read with this correction therein that the same may conform to the record of the case in the Patent Office.

Signed and sealed this 20th day of March, A. D. 1928.

Seal.
